UNITED STATES PATENT OFFICE.

WILLIAM A. SMITH, OF DENVER, COLORADO, ASSIGNOR TO THE DENVER ROCK DRILL MANUFACTURING CO., OF DENVER, COLORADO, A CORPORATION OF DELAWARE.

ROCK-DRILL.

1,293,225.

Specification of Letters Patent.

Patented Feb. 4, 1919.

Application filed March 19, 1917. Serial No. 155,830.

To all whom it may concern:

Be it known that I, WILLIAM A. SMITH, a citizen of the United States, residing at Denver, in the county of Denver and State of Colorado, have invented certain new and useful Improvements in Rock-Drills, of which the following is a specification.

The present invention relates to drilling apparatus and more particularly to that type in which the chuck and therefore the tool is rotated by means independent of the motor which delivers the drilling blow.

One of the objects of the present invention is to provide a relatively simple and practical structure that is also compact, and in which the various parts will effectively carry out their functions.

In the drawings:—

Figure 1 is a plan view of the preferred embodiment of the invention, portions being shown in horizontal section,

Fig. 2 is a vertical longitudinal sectional view therethrough.

Fig. 3 is a front elevation,

Fig. 4 is a view in section taken on the line 4—4 of Fig. 2,

Fig. 5 is a detail cross sectional view on the line 5—5 of Fig. 2.

Fig. 6 is a horizontal sectional view through the rotary motor and gear case.

Fig. 7 is a fragmentary longitudinal section through a portion of the structure shown in Fig. 5.

Similar reference numerals designate corresponding parts in all the figures of the drawings.

In the embodiment illustrated, a suitable support 6 is employed, having the usual longitudinal guideways 7, in which is slidably mounted a carriage or cradle 8 that may be adjusted by any desired means.

This carriage is shown as having suitable engagement with a feed screw, a portion of which is shown at 9. The carriage furthermore is provided at its rear end with semi-conical opposite projections 10 illustrated more particularly in Fig. 5. It is also provided at its front end with outstanding tapered flat sided projections 11 shown in Fig. 4.

Mounted upon the carriage or cradle is the drilling mechanism proper. The same consists of a cylinder member 12, within which reciprocates a hammer piston 13. The cyl-

inder member has a removable rear head 14 and a reduced head 15 which is preferably integral with the barrel of said cylinder forming an integral shoulder 16. The rear head 14 is provided with opposite semi-conical projections 17 that are disposed above the projections 10. Upon the carriage and engaged with said projections 10 and 17, are clamping washers 18 having conical sockets 19 that receive the projections 10 and 17. A bolt opening formed between the carriage and rear head 14 receives a bolt 20 that serves to bind the parts in associated relation and thus clamp the rear end of the drilling motor to the carriage.

The hammer piston 13 is of the reversible type, comprising a central head 21 having oppositely extending necks 22 of similar form and size. The head 21 operates in a central chamber 23, while the necks are located in reduced chambers 24, the parts being so constructed that the piston can be reversed and either end used as the advance or hammering projection. The said piston hammer is provided with a longitudinal bore 25 that is of the same diameter throughout its length and permits the passage therethrough of a liquid delivery tube 26 mounted in the rear head 14 and having a reduced extension 27 located in the front portion of the piston and preferably projecting beyond the same. This tube is for the purpose of delivering cleansing liquid into the drill bit, as will be readily understood, and the parts are so arranged that it will not interfere with the reversal of the piston hammer.

Mounted on the upper side of the drill actuating motor above described, is a drill rotating motor, the same consisting of a cylinder member 28 removably mounted on the drill actuating member by means of an integral collar 29 that surrounds the head 15 and is abutted against the shoulder 16. The lower side of this collar is provided with outstanding flat sided tapered projections 30 disposed over the projections 11, as shown in Fig. 4, the sets of projections being clamped together by plates 31 having tapered sockets that receive the same, these plates bridging the joint between the carriage 8 and collar and being held in assembled relation by the tie bolt 32. By having one set, as for example, the rear projections 10 and 17 coni-

cal and the front set with flat faces, it will be obvious that while the parts are securely clamped together, the flat faces will permit any relative difference in the relation of the parts and obviate strains that might arise if both sets of securing projections were conical and the sections thereof were slightly out of position.

The cylinder member 28 contains a rotary motor, preferably of well known type, and consisting of a pair of pistons 33 and 34, having intermeshing teeth. One of these pistons, as 33, is provided with a suitable roller bearing 35, the other carrying a shaft 36 that projects through the front wall 37 of the cylinder 28, said wall being preferably removable. On the projecting end of this shaft is located a pinion 38.

Mounted on the front end of the drill actuating motor is a rotatable chuck which includes a casing 39 containing a rotatable tool receiving member 40 having a suitable socket 41 in which the rear end of the tool 42 is engaged, so that it is readily removable, but will be rotated thereby. The member 40 is fixedly located within an outer sleeve 43, being connected to said sleeve by any suitable means, as for example, a threaded engagement 44, and the sleeve 43 is rotatable within the casing 39. This sleeve is provided at its rear end with an integral gear 45.

The front head 37 of the motor cylinder 28 is provided with a forwardly projecting wall 46, and the rear end of the casing 39 is enlarged, as shown at 47 and abuts against the front edge of said wall, thereby producing a gear case, in which the driving pinion 38 and the gear 45 are located. The pinion 38 is in mesh with a gear 48 located alongside the same, and this gear 48 is integral with or fixed to a pinion 49 that in turn meshes with the gear 45. It will thus be seen that a reducing train of gearing is provided between the rotary motor and the tool-receiving chuck for transmitting motion from the former to the latter.

The head 37 of the rotary motor cylinder member 28 is secured to said cylinder member by bolts 50, shown in Fig. 1, and the chuck casing 39 is clamped to the rotary motor and the latter in turn is clamped in position upon the front end of the cylinder member 12 by side bolts 51 engaged at their rear ends in ears 52 formed upon the rear head 14, and in ears 53 formed upon the said chuck casing 39. Springs 54 are preferably located on these bolts to take care of the usual vibration and jars incident to the operation of the apparatus.

For the purpose of delivering and controlling the supply of motive fluid to the mechanisms, the following instrumentalities are preferably employed. Formed upon the upper side of the barrel of the cylinder mem-

ber 12 is an enlargement 55, at the ends of which are provided transversely disposed valve casings 56 and 57. A suitable nipple 58 is connected to the valve casing 56 for supplying motive fluid from any suitable source, and directly in line therewith, is a rotatable throttle valve 59 having an exposed actuating handle 60. This throttle valve is provided with a lateral port 61 that is movable into and out of communication with passageways 62 and 63 that communicate with the chambers 24 for supplying motive fluid to the drill actuating motor, and thus effect the reciprocation of the hammer piston 13. It is believed to be unnecessary to enter into a detailed description of the operation of this hammer piston.

A branch passageway 64 leads from the valve casing 56 between the inner end of the throttle valve 59 and the nipple 58 and is in communication with one end of the other casing 57. In this valve casing is located a throttle valve 65 operable independently of the valve 59 by an exposed actuating device 66 that is located, however, adjacent to the actuating handle 60 of the valve 59, so that both are readily accessible to an operator. The valve 65 has a lateral port 67 therein, which is movable into and out of communication with a passageway 68 that leads to the rotary motor 28. A suitable packing 69 is preferably interposed between the rear wall of the motor cylinder and the adjacent end of the enlargement 55. The exhaust from said rotary motor takes place through a port 70 formed in the front head 37 of the rotary motor cylinder, which thus admits such exhaust into the gear casing. The said gear casing is in turn provided in its lower side with an outlet port 71 opening into a passageway 72 that leads to the atmosphere.

The portion of the enlargement 55 between the two valve casings 56 and 57 is hollowed out to produce a lubricant reservoir 73, to which access can be gained by means of a removable plug 74. This reservoir has outlet ports 75 and 76 in its ends, with which pockets 77 respectively formed in the valves 59 and 65 are arranged to communicate. The pockets also move into and out of communication with channels 78 that open respectively into the passageways 63 and 68. Consequently it will be evident that when the valves are turned to one position, the pockets 77 will fill with lubricant and when they are turned to their other positions, the pockets being brought into communication with the channel 78, the lubricant will flow therefrom and thus be delivered into the passageways. When so delivered the lubricant will be carried by the motive fluid through the working parts of the apparatus.

It is believed that the operation of the

mechanism will be readily understood. When motive fluid is admitted to the drill actuating motor by turning the throttle valve 59 in the proper direction, the hammer piston will be reciprocated and operates upon the rear end of the drill bit 42. In like manner when the throttle valve 65 is turned to bring the port 67 into communication with the passageway 68, the rotary motor will be operated, thereby rotating the chuck and the drill bit engaged therein. Either motor can be actuated independently of the other, the parts are relatively simple, and all are readily accessible.

15 From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or scope of the invention.

Having thus fully described my invention, what I claim as new, and desire to secure by Letters Patent, is:

1. The combination with a cylinder member and a hammer piston operating in the cylinder member, of a collar surrounding 30 and mounted on the cylinder member, a rotary drill receiving chuck at the front portion of the cylinder member, and a drill rotating motor connected to the collar and geared to the chuck.

35 2. In apparatus of the character set forth, the combination with a cylinder member having a reduced head portion, and a hammer piston having its hammer end operating in said head portion, of a collar surrounding said head portion, a rotatable drill receiving chuck in said head portion, and a drill rotating motor mounted on the collar and geared to the chuck.

3. In apparatus of the character set forth, 45 the combination with a drill actuating motor including a cylinder member, of a chuck rotating motor removably mounted thereon and abutted against a portion thereof, a chuck including a rotatable tool receiving member and a casing therefor, the latter being abutted against the chuck rotating motor and separable therefrom, and means for clamping together the drill actuating motor, the chuck rotating motor and the chuck casing.

4. In apparatus of the character set forth, 60 the combination with a drill actuating motor including a cylinder member having a reduced head, forming an external shoulder, of a chuck rotating motor including a collar surrounding the reduced head and bearing against the shoulder, a chuck including a rotatable tool receiving member and a casing therefor, the latter being abutted 65 against the chuck rotating motor and sep-

arable therefrom, and side bolts for clamping together the drill actuating motor, the chuck rotating motor and the chuck casing.

5. In apparatus of the character set forth, 70 the combination with a drill actuating motor including a cylinder member having a reduced head and a hammer piston operating in the cylinder member, of a rotary motor including a cylinder member having a collar surrounding the head, a rotatable chuck including a tool receiving member and a casing therefor, the latter being disposed in advance of the rotary motor, a gear case formed between the rotary motor and chuck, gearing for transmitting motion 80 from the rotary motor to the tool receiving member, and means for securing the parts together.

6. In apparatus of the character set forth, 85 the combination with a drill actuating motor including a cylinder member, of a rotatable chuck, a chuck rotating motor carried by the drill actuating motor cylinder member, motive fluid supply means including a common chamber on the cylinder member 90 and separate passageways formed in the walls of the cylinder member and leading from the chamber to the two motors respectively, and independently manually operable throttle valves located side by side in 95 one side of said cylinder member for respectively controlling the passages, to permit either motor to be operated independently of the other.

7. In apparatus of the character set forth, 100 the combination with a drill actuating motor including a cylinder member, of a rotatable chuck, a chuck rotating motor carried by the drill actuating motor cylinder member, motive fluid supply means including 105 a common chamber on the cylinder member and separate passageways leading from the chamber to the two motors respectively, transversely disposed valve casings located side by side at one side of the cylinder member and including respectively the passageways, and rotary valves in the casings, respectively controlling the passages to permit either motor to be operated independently of the other, said valves having adjacent actuating means at corresponding ends.

8. In apparatus of the character set forth, 110 the combination with a drill actuating motor including a cylinder member, of a rotatable chuck, a chuck rotating motor carried by the drill actuating motor cylinder member, motive fluid supply means communicating with both motors, spaced valve casings, a lubricant reservoir between the 115 casings communicating therewith, and valves in said casings respectively controlling the supply of motive fluid to the motors and the delivery of lubricant from the reservoir to said motors.

9. In apparatus of the character set forth, the combination of a drill actuating motor, of a drill rotating motor, a drill receiving chuck, gearing between the rotating 5 motor and chuck, a casing inclosing the gearing, means for supplying motive fluid to the motor, means for delivering the exhaust from one of the motors to the gear casing, and means for delivering lubricant 10 to the motive fluid supply.

10. In apparatus of the character set forth, the combination with a drill actuating motor including a barrel, of a drill rotating motor mounted on the barrel, means 15 in rear of the drill rotating motor for de-

livering motive fluid thereto, means for introducing lubricant to the motive fluid supply, a rotary drill receiving chuck, gearing in advance of the rotating motor and connecting the same with the drill receiving chuck, a casing inclosing a gearing, and means for delivering the exhaust from the rotating motor into the gear casing. 20

In testimony whereof, I affix my signature in the presence of two witnesses.

WILLIAM A. SMITH.
